Primary Examiner — Susan Moon Lee

(74) Attorney, Agent, or Firm — Wayne J. Colton, Inc.

(57) **CLAIM**

The ornamental design for a feed channeling insert for barrel type animal feeders, as shown and described.

DESCRIPTION

FIG. 1 is a top perspective view of a feed channeling insert for barrel type animal feeders, showing my new design;

FIG. 2 is a bottom perspective view thereof;

FIG. 3 is a top plan view thereof;

FIG. 4 is a bottom plan view thereof; and,

FIG. 5 is a cross-sectional view, taken through cut line 5-5 of FIG. 3, thereof.

1 Claim, 5 Drawing Sheets(56)
